VARIABLE RACING GAME APPARATUS

Anton F. Burkhardt, New York, N. Y.

Application November 8, 1949, Serial No. 126,172

3 Claims. (Cl. 273—86)

1

This invention relates to variable racing game apparatus and has for its object the provision of a device of the class described which may be played by adults and which also may be used as an animated toy by children.

Another object is to provide an amusement device wherein a plurality of figures such as horseback riders, automobiles, dogs or any other figures are arranged to travel in a course simulating a race track, said figures being driven by simple means easily operated by the user and which will cause all said figures to advance along the track until one of them reaches the finish line, it being practically impossible for the user to predetermine the winner.

Further objects and advantages will be apparent from the following specification and accompanying drawings wherein, by way of illustration, a preferred embodiment of the invention is disclosed. It will be understood, however, that various modifications may be made in the construction disclosed without departing from the scope of the invention, which is as defined in the appended claims.

In the accompanying drawings:

Figure 1 is a perspective view of an amusement device embodying the invention;

Figure 2 is a view of the winding mechanism used in the device shown in Figure 1 with the cover removed and in starting position;

Figure 3 is a fragmentary view of the mechanism Figure 2 with the winding shaft moved to the extreme right;

Figure 4 is a view similar to Figure 3 with the shaft moved to the left;

Figure 5 is a view partly in section of an alternate type of operating mechanism which can be used instead of that shown in the preceding figures; and

Figure 6 is a top plan view of the mechanism shown in Figure 5.

Referring to Fig. 1 the numeral 10 denotes the baseboard of the device which may be suitably colored to simulate a race track. This has a suitable mark or indication at 11 to indicate the starting line for the horses or other figures 12 to 17 inclusive.

At the right hand end of the baseboard as shown in the drawing is mounted a suitable casing 18 for the winding mechanism which is provided with a removable cover 19. The ends of this casing are slotted as indicated at 20 to receive ends 21, 22 of a shaft which extends through the casing, as best seen in Fig. 2, the arrangement being such that when the cover 19 is removed, the shaft can be easily removed

2

from the casing in order to renew or adjust the cords which will presently be referred to.

While the shaft having journalled ends 21, 22 may be of any form, the contour of same is irregular as indicated by the enlarged sections 23 to 28 inclusive. The shaft also has the reduced sections 29 to 34, inclusive. It will be understood that the general contour of the shaft may vary within wide limits.

The shaft is provided at one or both ends with crank handles as indicated at 35. Figures 12 to 17 inclusive are connected to cords 36 to 41 inclusive which pass through apertures in the side wall of the casing 18, one of these apertures being indicated by the numeral 42.

It will be noted from a study of the drawings that the winding shaft contains sections of larger and smaller diameters indicated by the numerals 23 to 34, inclusive and may be moved in two directions. This shaft is generally indicated by the numeral 43 and may be revolved by turning the crank 35 and at the same time or at any time, the shaft may also be moved longitudinally, the bearing surfaces 24, 22 thereof being of sufficient length to allow the shaft to be moved from its normal or central position as shown in Fig. 2 to the extreme right as shown in Fig. 3, until the collar 44 on said shaft is brought into contact with the inner wall of the end member 45 of the casing 18. Also, if the shaft is moved to the extreme left as in Fig. 4, the collar 46 will be brought into engagement with the left hand end 47 of casing 18.

It will now be seen that if all the figures 12 to 17 inclusive are brought to the starting line 11 or lined up at any other mark transverse the baseboard 10, the cords 36-41 inclusive will all be in the position shown in Fig. 2. But, if as the shaft 43 is revolved and is moved longitudinally to the position shown in Fig. 3, then the cords 36-41 inclusive will each be subjected to a different rate of wind-up and, if the shaft is moved to the left, as shown in Fig. 4, the rate of wind-up of each cord will again be varied. This is because of the fact that the wind-up of each cord depends on the resultant of three components, to wit; (a) the rotary motion of the shaft; (b) the diameter of the shaft such as 28, 33 on which a cord such as 41 is being wound at any particular instant; and (c) the change in said diameter due to the longitudinal motion of the shaft.

The result is, again taking cord 41, for example, that starting with the shaft 43 in the position shown in Fig. 2 and rotating it clockwise (looking at the right hand end), the cord 41, starting at 41a will rapidly advance the figure

17 connected thereto as the cord rolls over the enlarged portion 28 of the shaft, but as soon as the cord reaches the reduced diameter 33 as indicated at 41b, the forward movement of figure 17 is diminished but is again increased when the cord reaches the enlarged diameter 27 of the shaft.

Also referring to cord 39, it starts to move from the position 39a on the enlarged diameter 26 but decreases its movement when it reaches the small diameter or neck 26a, but rapidly increases when the part 39b thereof encounters the enlarged portion 31a of the shaft.

In some cases the cords actually cross each other as indicated in Fig. 4. Here the cord 41 starting at 41a is first wound over the reduced diameter 33 as indicated at 41b, and then, because of the longitudinal movement of the shaft, crosses itself as indicated at 41c, and passes over the large diameter 28.

The result is that when the shaft 43 is operated in the manner described (and it requires no skill to so operate it as the user merely revolves the shaft and at the same time moves it longitudinally), while the movement of the figures 12 to 17 inclusive is always forward, the rate of said movement is continual and practically unpredictable to the user of the device and to the onlookers.

First one of the figures will advance rapidly, then slow up, then another figure will advance and perhaps almost reach the finish line 48 and then drop back while another figure advances. The result is a perfect simulation of a horse race in miniature and up to the last second or two it is impossible for an onlooker to predict the winner.

It will be noted that the shaft or spindle 43 is easily constructed of wood or the like, that the entire device is simple to manufacture and may therefore be sold as a toy.

Obviously the device may be made of any size and if desired the figures 12 and 17 inclusive can be mounted on rollers and provided with live riders where the device is used for outdoor amusement in parks, carnivals or the like.

In Figs. 5 and 6 is shown an alternate form of the device. Here, instead of the shaft 43 as previously described, a shaft 49 is employed which is of irregular contour but having the enlarged and reduced sections as described in connection with the shaft 43, or being constructed so that the shaft 49 has a plurality of cam surfaces having the outwardly extending lobes 49a, 49b, 49c, 49d and 49e and the cut-away portions of less average diameter 49f, 49g and 49h.

When the cams just referred to are used, the shaft need not be moved longitudinally as described in connection with shaft 43, but may be mounted for such longitudinal motion, in which event it will be obvious that the variation of movement produced by the cam surfaces would be varied by said longitudinal motion.

Three cords which may be connected to the figures are indicated at 50, 51 and 52 and, as the figures are exactly the same in this modification as in the device described in connection with Figs. 1 to 4 inclusive, the figures are not shown and described in detail, but one is indicated at 53 on the outer end of cord 50.

The inner ends of the cords, instead of being fastened to the shaft 43 as previously described, are secured to spools, one of which is indicated at 54 and, as all of these spools are alike, only one will be described.

The spools are mounted on a shaft to which is secured a rubber-tired wheel 55. The spools are revolved by the wheels 55 bearing against the cam surfaces on the shaft 49. The spools and wheels are mounted in suitable bearings in the outer end of a sleeve 56 slidably mounted in a socket 57 and urged outwardly therefrom by a spring 58. The sleeve 57 is suitably mounted in an upright 59 which in this modification would be equivalent to the front of the casing 18, the cam being mounted in a suitable casing in the manner described in connection with the shaft 43.

The action of the modified device just described is substantially the same as that shown in Figs. 2 to 4, inclusive, and the same practically infinite number of variations in the relative position of the figures can be obtained.

The modification shown in Figs. 5 and 6 is particularly useful where it is desired to complete a race with a single turn of the cam shaft 49 and the contour of said shaft may be made large enough to accomplish this. It will also be noted that said contour varies not only diametrically but also longitudinally, as indicated in section in Fig. 6.

It will be observed from the foregoing that the figures are movable along the base in substantially parallel lines and that by turning the shaft at a uniform angular velocity, the figures will be moved at relatively varying linear speeds.

This is accomplished either by the shaft arrangement shown in Figs. 1 and 4 or by the modification shown in Figs. 5 and 6.

What is claimed is:

1. In a device of the character described, a supporting framework including a baseboard having a pair of upstanding members secured thereto and adapted to support a shaft therebetween; a rotatable shaft supported by said members and longitudinally movable therein and having a plurality of sections integral with said shaft, said sections being of varying diameters along the length of said shaft, each of said sections having an arcuate profile extending in the axial plane of said shaft, each of said profiles differing from the profile of any other section; a plurality of figures movably mounted on said baseboard; and a flexible member connected to each of said figures and to each of said shaft sections whereby said figures may be moved by rotating said shaft to wind said flexible members about said sections of varying diameters while same are all revolving at the same axial speed.

2. In a device of the character described, a base, a plurality of figures supported on said base and adapted to be moved thereover in substantially parallel paths, a rectangular casing supported on said base and extending transversely thereof, and means in said casing including a shaft and flexible members secured directly thereto and operatively connected to said figures for moving same as aforesaid at relatively variable linear speeds as said shaft is revolved at any given radial speed, said flexible members being wound around arcuate profiles on said shaft, each of said profiles being different from any other profile.

3. In a variable racing game apparatus, a base; a plurality of figures supported on said base and adapted to be moved thereover in substantially parallel paths; a casing having upstanding side walls supported on said base and extending transversely thereof, said side walls having U-shaped slots therein extending downwardly toward said base; a shaft supported on the bottom

of said U-shaped slots, said shaft being adapted to be removed and replaced in said slots as a unit, said shaft being longitudinally slidable in said slots, said shaft having a plurality of sections integral therewith of varying diameters, each of said sections having an arcuate profile extending in the axial plane of said shaft, each of said arcuate profiles differing from the profile of any other section; and flexible members connected to said figures and to said shaft to move said figure as said flexible members are wound about said arcuate profiles by the revolution of said shaft, said figures being moved thereby at relatively variable linear speeds as said shaft is revolved.
